UNITED STATES PATENT OFFICE.

WILLIAM J. POSSONS, OF CLEVELAND, OHIO.

CARBON-BAKING BOX.

SPECIFICATION forming part of Letters Patent No. 331,440, dated December 1, 1885.

Application filed April 11, 1884. Serial No. 127,490. (No model.)

To all whom it may concern:

Be it known that I, WILLIAM J. POSSONS, of Cleveland, in the county of Cuyahoga and State of Ohio, have invented certain new and 5 useful Improvements in Carbon-Baking Boxes; and I do hereby declare the following to be a full, clear, and exact description of the invention, such as will enable others skilled in the art to which it pertains to make and use the 10 same.

My improvement relates to the boxes or receptacles used for holding electric light and other carbons during the baking process. It is customary to make such receptacles in the 15 shape of plain cast-iron boxes, the carbons being packed therein with sand and covered with a plate of suitable material resting upon the sand and sealed to the sides with suitable luting. Such boxes, however, under the intense heat of the baking-oven and the pressure of the sand from within frequently bulge out and crack at the sides, thus burning the carbons and allowing them to become displaced and warped. To obviate these difficulties, I 20 form the walls of the receptacle of slabs or plates of refractory material, such as soapstone, which form a non-yielding support for the carbons and complete protection against burning. These plates may be supported by any suitable 25 means, but I prefer to use them as a lining to the customary iron box, the box holding the plates in their proper positions and the plates preventing undue strain upon the sides of the box, as well as insuring the carbons 30 against burning and displacement. With this safeguard I am enabled to pack the carbons vertically instead of horizontally, without the risk of their falling apart and becoming warped. This allows about fifty per cent. 35 more carbons to a box and decreases largely the percentage of crooked carbons. By the use of these refractory plates with the iron boxes the latter lasts longer, whereby is effected a saving not only in the cost of boxes, but in 40 the waste which generally ensues when a box breaks. To further secure this object, and to prevent the destruction of the seal by the sinking of the cover, I form or cast a rib around the inside of the iron box a slight distance below the top, for the purpose of adding 45 rigidity to the sides and forming a support for cover,

My improvements more specifically comprise a supplementary or false bottom, supported by suitable ribs a slight distance above 55 the bottom of the box, and upon which the ends of the carbons rest. It serves to equalize the heat and prevent the burning of the ends of the carbons. I also improve the construction of the box by casting or forming ribs 60 upon the under surface of the bottom, to allow of the free circulation of the heat and to add strength to the box.

In the accompanying drawings, Figure 1 represents a cross-section of a filled box. Fig. 65 2 is a longitudinal section of the box, ready for filling.

a is the outer box, ordinarily of cast-iron. *b* is the cover, which may be a refractory tile of any suitable material, and *c* is a heavy 70 strengthening and supporting rib cast with the box, and upon which the cover rests. *d* are the slabs of soapstone forming the refractory lining for the walls of the box. They may be placed up close to the walls, but I prefer 75 to leave a small space between them, as shown, for a packing of sand, which is poured in through the crevice at the top.

The supplementary bottom *e* may be made of a piece of sheet-iron and held up by ribs *f*, 80 secured to it by rivets or otherwise. I also reserve the right to use in connection with the slabs of soapstone on the sides a similar one on the bottom in place of the iron bottom *e*.

At *g* are shown the ribs cast on the bottom 85 of the box for the purpose above set forth.

The supplementary bottom and sides having been put in place, the inner space is completely filled with carbons *h*, points downward, as shown. Sand is then poured in until all 90 the interstices *j* are filled and the carbons covered about an inch deep. The cover is then put in place on the rib *c* and sealed with refractory luting *i*.

A box constructed and protected in this way 95 will stand a great many successive heatings without injury, and when the iron does give way the refractory slabs still prevent injury to the carbons.

Having thus described my improvements, 100 what I claim as new and of my invention is—

1. A receptacle for holding carbons during the baking process, consisting of a metal box provided with a cover, and independent slabs

- or plates of refractory material, substantially as described, located adjacent to the inner sides of the box, substantially as set forth.
2. A receptacle for holding carbons during the baking process, consisting of a metal box provided with a cover, and slabs or plates of refractory material as described, situated within the box at its sides and ends, substantially as set forth.
- 10 3. A receptacle for holding carbons during the baking process, consisting of a metal box having a lining of refractory material, and having a supplemental floor or bottom provided with heat circulating spaces on its under 15 side, substantially as set forth.
4. A receptacle for holding carbons during the baking process, consisting of a cast metal box having a lining of refractory material and having inwardly-projecting ribs or ledges, in combination with a cover adapted to be supported on said ribs or ledges, substantially as set forth. 20
- In testimony whereof I sign this specification, in the presence of two witnesses, this 5th day of April, 1884.

WILLIAM J. POSSONS.
